UNITED STATES PATENT OFFICE.

HENRY JOHN WEGNER, OF AUBURN, NEBRASKA.

GASOLENE-ENGINE.

No. 923,093.

Specification of Letters Patent. Patented May 25, 1909.

Application filed August 1, 1907. Serial No. 386,641.

To all whom it may concern:

Be it known that I, HENRY JOHN WEGNER, a citizen of the United States, residing at Auburn, in the county of Nemaha and State 5 of Nebraska, have invented certain new and useful Improvements in Gasolene-Engines; and I do declare the following to be a full, clear, and exact description of the invention, such as will enable others skilled in the art 10 to which it appertains to make and use the same.

This invention relates to internal combustion engines, and more particularly to that class of said engines in which liquid 15 fuel is used for causing the explosion.

The object of the invention is to provide means whereby the engine may be started with a volatile fluid such as naphtha or gasoline and run until the explosion chamber be- 20 comes sufficiently heated to volatilize heavier liquid such as kerosene or denatured alcohol, whereby the engine may be run as efficiently upon the same amount of a cheaper grade of kerosene or heavier oil that was required of 25 gasoline or the lighter oil, and accomplishes the same result, thereby effecting a considerable saving in the expense or cost of the fuel as heretofore used.

Efforts have been made heretofore to use 30 the heavier and cheaper liquids with a greater or less degree of success. I have dis- covered that by properly mixing the proper parts of kerosene, air and water, such mix- 35 ture can be used in an ordinary engine with great success, as it does not injure the engine any more than does a lighter and more costly liquid.

With these and other objects in view, the 40 invention consists of certain novel features of construction, combination and arrange- 45 ment of parts, as will be more fully described and particularly pointed out in the appended claims.

In the accompanying drawings, Figure 1 is 45 a diagrammatic view partly in section showing a portion of an internal combustion engine provided with one means for feeding different kinds of fuel thereto. Fig. 2 is an 50 end elevation of an engine provided with a slightly modified form of means for supplying fuel thereto.

In the embodiment illustrated an engine cylinder 1 is shown, which may be of any

ordinary construction provided with a reservoir or carbureter 2, and having a head 1^a 55 provided with a spring pressed inlet valve 1^b.

Communicating with the reservoir 2 are two pipes 3 and 4, which are provided with three-way valves 5 and 6, respectively. Con- 60 nected to communicate with the pipe 3 are two supply pipes 7 and 8, one of which com- 65 municates with the gasolene tank 9 and the other with the kerosene tank 10 and a three- way valve 5 is arranged at the junction of the pipes 3, 7 and 8, and is operable to bring one of the pipes 7 or 8 into communication with the pipe 3 when desired, and to shut off the other pipe.

A pump 16 is connected with the supply pipe 8, and is adapted to be operated by the 70 engine in any ordinary manner for the pur- pose of conveying fuel from the tank 10 to the reservoir 2. Connected to communicate with the pipe 4 are two pipes 11 and 12, the pipe 11 communicating with the gasolene 75 supply tank 9, and being designed to return gasoline from the reservoir 2; after it reaches a predetermined point; the other pipe 12 is a return pipe for returning the kerosene to said tank 10. A three-way valve 6 is arranged at 80 the junction of pipes 4, 11 and 12, and is operable to bring either of the pipes 11 or 12 into communication with pipe 4, as desired. A pump 15 is connected with the supply pipe 7 and is operated by the engine in the same 85 manner as the pump 16, and is adapted to force the fuel from the tank 9 to said reser- 90 voir 2.

The pipe 4 extends into the reservoir 2 preferably to a point about midway the height thereof and constitutes an overflow to 95 permit the oil when it reaches a predeter- 90 mined point to be returned to its source of supply when the pump is in operation.

In the drawing the valves are shown in the 95 position in which they are turned at the starting of the engine.

The reservoir 2 is provided with a valved outlet 26, arranged at the normal liquid level of said reservoir, and the valve of this outlet 100 has a stem 27 extending through the outer end of the reservoir 2 and is provided with a handle for operating the outlet valve to vary the amount of oil to be fed therethrough.

A pipe 28 of comparatively large diameter 105 surrounds the valve 1^b at one end and the

other end thereof is open to the atmosphere at a point somewhat remote from the inlet valve 1^b. A nozzle 29 opens from the valved oil outlet 26 into said pipe 28, and a nozzle 30 connected with a water supply pipe 31 also opens into said pipe 28 at a point between the open or air inlet end and the oil nozzle. This pipe 31 is preferably provided with a stop cock 31' for regulating the supply of water to be fed through the nozzle 30. When the engine is in operation and the piston 32 moves inward it creates a vacuum in said cylinder which opens the valve 1^b against the tension of the spring, and the opening of this valve causes suction in the pipe 28 and draws therein oil through the nozzle 29, water through the nozzle 30 and air through the open outer end of the pipe 28, and these ingredients are thoroughly mixed and commingled in the pipe 28 before entering the combustion chamber of the engine.

When it is desired to start the engine, the cock 31' being closed, the three-way valve 5 is operated to cut off communication between the pipe 3 and the pipe 8, and to bring the pipe 3 into communication with the gasoline supply pipe 7, (as shown in Fig. 1) and the pump 15 being in operation, the gasoline is forced through said pipe 7 into the reservoir 2 and passes out through the valved outlet 26 into the combustion chamber in the usual manner. The overflow of gasoline passes down through the pipe 4 through the pipe 11 back to the tank 9, the valve 6 having been operated to cut off communication with the pipe 12. After the explosion chamber has been heated to the proper degree by the explosion of the lighter fuel therein the cock 31' is opened and the three-way valve 5 is operated to shut off the supply of the lighter fuel and to turn on the supply of the heavier fuel, which flows through the pipe 8 into the pipe 3, and from thence into the reservoir 2, and after reaching a predetermined overflow point passes back through the pipe 4 into the return pipe 12 which conveys it to the tank 10, the valve 6 having been previously operated to cut off communication of the pipe 4 with the pipe 11. The return pipes 11 and 12 are provided with stop cocks 17 and 18 respectively for controlling the passage of the excess of fuel therethrough as it is being returned to the tanks 9 and 10 respectively.

Cross pipes 13 and 14, connect the pipes 7 and 11, 8 and 12, respectively, and are provided with stop cocks 13' and 14'. These cross pipes 13 and 14 are designed to convey the gasoline or kerosene, as the case may be to its return pipe and back to the tank when its respective pump is in operation and the valve 5 is turned to cut it off from the reservoir 2. For instance, when the valve 5 is turned to cut off the gasoline supply pipe 7 from pipe 3, the stop cock 13' and the cross pipe 13 is opened and the

pump 15 being continuously in operation, the gasoline is pumped through pipes 7, 13 and 11 back to tank 9. When valve 5 is turned to bring pipe 7 into communication with pipe 3 and cut off pipe 8, the cock 13' is closed and cock 14' in pipe 14 opened and while the gasoline is pumped into reservoir 2, the kerosene circulates through pipes 8, 14 and 12 back and to tank 10 and continues to so circulate until the cock 14' is closed and valve 5 opened to turn the kerosene into the tank or reservoir 2. By this construction the pumps 15 and 16 may remain always in operation during the running of the engine.

With small engines one of the pumps may be dispensed with and the supply of gasoline or lighter oil can be placed in a small vessel 21, which is located above the reservoir 2 and the feed will be effected by gravity. By the time the oil in the vessel 21 has been consumed the engine will be sufficiently hot for the use of the heavier grade of fuel, when the valve 22 in the supply pipe 23 is turned and the supply of fuel from the tank 24 is permitted to enter the engine, as above described, and the surplus is returned through the pipe 25.

In using the heavier grade of oil a greater or less amount of residue is apt to be deposited in the engine. It is therefore preferable to cut off the supply of the heavier grade a short time previous to the shutting down of the engine and to turn on the lighter grade of oil, which will prevent the deposit from the heavier grade of oil, permitting it to be carried in through the exhaust and thereby leaving the engine perfectly clean for starting up.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention as defined in the appended claims.

I claim as my invention:—

1. In an attachment for gas engines, two sources of fuel supply, each adapted to communicate with the reservoir of the engine and to be provided with a return pipe, means for admitting fuel to the reservoir from either source of supply, means for returning the excess of said fuel to its respective supply, and means for mixing the supply of the heavier grade with the proper amount of air and water to adapt it to be exploded in a heated engine.

2. In an attachment for gas engines, two sources of fuel supply, a supply pipe from each source communicating with the reser-

voir of an engine, a three-way valve and a return pipe for each supply pipe, a valve for each supply pipe, a pump connected with each supply pipe, and means for mixing the heavier grade of fuel with the proper amount of air and water to adapt it for being exploded in a heated engine.

In testimony whereof I have hereunto set my hand in presence of two subscribing witnesses.

HENRY JOHN WEGNER.
